UNITED STATES PATENT OFFICE.

CLEMENCE O. SCHULZE, OF BURLEY, IDAHO.

SACK NEEDLE.

Application filed December 19, 1922. Serial No. 607,782.

To all whom it may concern:

Be it known that I, CLEMENCE O. SCHULZE, a citizen of the United States of America, residing at Burley, in the county of Cassia and State of Idaho, have invented certain new and useful Improvements in Sack Needles, of which the following is a specification.

This invention relates to certain new and useful improvements in sack needle and has particular reference to a needle adapted for sewing sacks or cloth bags with the eye portion of the needle being constructed in a manner to permit easy and quick threading of the needle.

The primary object of the invention has particular reference to a sack or bag sewing needle wherein the eye portion embodies resilient side arms carried by the body portion of the needle and wherein the outer ends of the arms are normally closed to provide a retaining eye for the thread.

A further object of the invention embodies in the eye construction of a needle as above set forth, having the contact faces of the outer ends of the arms formed with interengaging parts with the thread or sewing cord inserted between the outer ends of the interengaging parts to permit free passage to the eye of the needle.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of a sack or bag sewing needle constructed in accordance with the present invention showing initial position of the thread or cord during the threading operation of the needle,

Figure 2 is a view similar to Fig. 1 showing the position of the thread or cord threaded into eye opening of the needle,

Figure 3 is a view similar to Figs. 1 and 2 showing the position of the thread when the same is to be removed from the needle,

Figure 4 is a fragmentary side elevational view, partly in section of the eye end of the needle showing the tongue and groove connection between the adjacent faces of the

outer ends of the arms surrounding the eye opening of the needle,

Figure 5 is a fragmentary side elevational view, similar to Fig. 4 showing the position assumed by the side arms of the needle eye when a cord or thread is forced therebetween during the threading operation of the needle,

Figure 6 is a fragmentary edge elevational view of the eye end of the needle, and

Figure 7 is an end elevational view of the needle.

The sack or bag sewing needle disclosed in this application embodies a central body portion 1 of circular or oval formation in cross section that carries a bag entering or pointed end 2 of diamond shape in cross section, while the opposite end of the central body portion 1 carries the eye and threading section of the needle.

The eye section of the needle is formed by the provision of a pair of resilient side arms 3 and 4 spaced to provide a thread receiving eye 5 with the outer end of the eye 5 closed by shoulders 6 and 7 carried respectively, by the side arms 3 and 4. As shown in Fig. 4, the shoulders 6 and 7 contact over the major portions of their lengths while the outer ends thereof are curved outwardly at

80 at 8 and merge into the outer sides of the resilient side arms 3 and 4 to provide a terminal substantially V-shaped recess in the end of the needle for receiving the cord or thread during the threading operation. To pro-

90 vide for an interlocking engagement between the shoulders 6 and 7, and also to prevent accidental displacement of the thread from the eye 5 of the needle, the inner face of the shoulder 6 carries a rib or tongue 9 that is received in a groove 10 formed in the adjacent contacting face of the arm shoulder 7 as clearly shown in Figs. 4 and 5, the shoulders 6 and 7 being maintained in intimate

95 contact with each other by the resiliency of 100 the side arms 3 and 4.

During the threading operation of the needle, the thread T is placed in the position shown in Fig. 1 in contact with the curved ends 8 of the shoulders 6 and 7 and by pulling inwardly upon both strands of the

105 thread T, the shoulders 6 and 7 carried by the resilient arms 3 and 4 are forced apart as shown in Fig. 5, permitting the passage of the looped end of the thread T between the arm shoulders 6 and 7 and into the eye 5, said thread then assuming the position

shown in Fig. 2, the strain upon the thread during the sewing operation being placed upon the inner edges of the arm shoulders 6 and 7. If it is desired to unthread or remove 5 the thread T from the needle, one strand of the thread is placed in the position shown in Fig. 3, and by pulling in the direction of the arrow the thread is forced between the arm shoulders 6 and 7 to displace the rib or 10 tongue 9 from the groove 10 and permit the looped portion of the thread to be received in the needle eye 5 and thereafter completely removed from the needle. It will be noted that the resiliency of the arms 3 and 4 maintains 15 intimate contact between the arm shoulders 6 and 7, and by the provision of the tongue and groove connection 9 and 10 lateral movement of said shoulders is eliminated. Also, the curved outer ends 8 of 20 the arm shoulders 6 and 7 provide for the correct positioning of the thread T during the threading operation of the needle, attention being called to the fact that the thread is introduced into the eye 5 of the needle 25 from the terminal end of the needle, or, in other words, the looped portion of the thread as shown in Fig. 1 is moved axially of the needle to place the thread in the eye portion thereof, and in this position, the 30 looped portion of the thread engages either of the shoulders 6 or 7 during the sewing operation, and should said thread during said sewing operation, be positioned directly between the arm shoulders 6 and 7, the strain 35 will be taken up by the adjacent ends of the tongue and groove 9 and 10.

While there is herein shown and described the preferred embodiment of the present invention, it is nevertheless to be understood that minor changes may be made therein 40 without departing from the spirit and scope thereof.

What is claimed as new is:—

In a needle of the type described, an elongated body portion pointed at one end and 45 having a pair of spaced resilient arms at its opposite end, aligned engaging edge abutting shoulders carried by the adjacent sides of the outer ends of said arms, said shoulders being elongated in the direction of the length of 50 said body portion with their outer ends tapered outwardly to form a shoulder wedging thread socket and with their inner ends squared to resist any thread wedging action, 55 the space between the resilient arms inwardly of the shoulders constituting an eye portion, and a connection between the full lengths of the contacting edge faces of said shoulders including a tongue centrally carried by the contacting edge face of one shoulder, and the opposite shoulder being formed with a central groove cooperating 60 with the tongue, said connection being broken by a movement of the shoulders in the direction of their common central plane with 65 said shoulders remaining in the same plane and with the thread extending at right angles to said central plane during insertion thereof into the eye portion of the needle.

In testimony whereof I affix my signature.

CLEMENCE O. SCHULZE.
